[57] CLAIM

The ornamental design for a combined telephone enclosure and advertising unit, as shown and described.

DESCRIPTION

FIG. 1 is a front perspective view of a combined telephone enclosure and advertising unit showing my new design;

FIG. 2 is a front elevational view thereof;

FIG. 3 is a bottom plan view thereof;

FIG. 4 is a side elevational view thereof taken from the left of FIG. 2, the opposite side being substantially a mirror image thereof;

FIG. 5 is a top plan view thereof; and

FIG. 6 is a rear elevational view thereof.

FIG. 1**FIG. 2**

FIG. 3**FIG. 4**Fig. 5

Fig. 6
